UNITED STATES PATENT OFFICE.

RICHARD E. KIRTLEY, OF KANSAS CITY, MISSOURI.

CHEMICAL-CONTAINER.

1,371,627.

Specification of Letters Patent. Patented Mar. 15, 1921.

Application filed March 26, 1919. Serial No. 285,305.

To all whom it may concern:

Be it known that I, RICHARD E. KIRTLEY, a citizen of the United States, residing at Kansas City, in the county of Jackson and

5 State of Missouri, have invented certain new and useful Improvements in Chemical-Containers; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention relates to chemical containers for introducing suitable chemicals into an oil well to remove accumulations, such as paraffin, asphaltum, and other objectionable surfaces which have a tendency 20 to clog up the interstices of the reticulated lining in soft sand wells or the capillaries in hard sand wells.

It is well known that oil wells sometimes cease to flow because the capillaries or the 25 interstices of the lining become clogged on account of accumulations, such as paraffin, asphaltum, and the like. If these accumulations are removed the well will be restored.

Various attempts have been made heretofore to remove these accumulations, for example, by introducing steam or acids to dissolve the hydrocarbon solids. Steam has not proved efficient, and while chemicals of 30 various kinds efficiently remove the accumulations, it has been the practice heretofore to pour large quantities into the well with the result that a considerable portion of the chemical is lost by adhering to the side above the zone to be treated.

40 It is the purpose of my invention to apply the chemicals locally so that relatively small quantities will suffice.

In carrying out my invention I provide a container which will hold the requisite 45 charge of chemicals and which may be lowered into the bottom of the well where it is to be applied before it is released, and after it has reached the zone of application to discharge the chemicals to permit it to attack 50 the accumulations adhering to the surrounding walls so that the flow of oil from surrounding strata may be resumed.

In the drawings,

Figure I is a view partly in section and 55 partly in elevation of a container construct-

ed in accordance with my invention, the outer orifice for the container being sealed.

Fig. II is a similar view with the seal broken to permit the chemicals to flow into the interior of the well.

60

Fig. III is a side elevation view of a container complete.

Fig. IV is a detail perspective view of the latching device for retaining the seal, disrupter and nozzle in retracted position.

65

Fig. V is a sectional view through a modified form of container.

Fig. VI is a fragmentary sectional view of the same, showing position of the parts when the seal is broken.

70

Fig. VII is a sectional view on the line VII—VII of Fig. VI.

Referring now to the drawings by numerals of reference:

1 designates the container which may 75 consist of a receptacle made up of a plurality of pipe sections, the upper one of which is provided with bail 2 by means of which a cord, cable or rope may be attached to lower the device into the well. 80 The bottom of the container is provided with a sleeve 3 engaging a head 4 which constitutes part of the seal for the receptacle, the head 4 having a central orifice 5 in which is a tube 6 surrounding a vertically 85 slidable seal disrupter and nozzle 7, which in Figs. I and II as shown as a hollow tubular member provided near its upper end with a plurality of perforations 8, the upper end of the nozzle 7 being provided with a 90 head 9, which closes that end of the nozzle. Threaded into the head 4 is a sleeve 10 between which and the tube 6 are spring latch members 11 and 12, the upper outer ends 13 and 14 of which bear against the head 95 4 and the lower ends of which are provided with jaws 15 and 16 to engage the collar 17 on the nozzle 7, when the nozzle is in retracted position as shown in Fig. II.

At the bottom of the standard or nozzle 100 7 is a foot or base 18 which may be of any approved construction and which may be suitably attached thereto, but I have here shown it as consisting of a disk having bracket arms 19 and 20, whereby it may be 105 secured to the open end of the member 7 so that the chemical entering the orifices 8 may discharge into the well.

When it is desired to introduce chemical into the well the container is sealed by seat-

110

ing the valve head 9 upon the head 4 and sealing the same by a disruptable material, such as wax or the like, as shown in Fig. I.

The device is then lowered into the well 5 until the base or foot 18 strikes against the bottom when the weight of the receptacle will be sufficient to cause the valve head 9 to disrupt or break through the wax and assume a retracted position as shown in Fig. 10 II, and to be held in such position by engagement of the jaws 15 and 16 with the collar 17 as shown. The chemicals will then discharge through the orifices 8 and the discharge end of the nozzle or standard 7 into 15 the well and locally attack the wall thereof to free it from objectionable accumulations.

In Figs. V to VII, both inclusive, the receptacle 1 is provided with a head 21 having a valve seat 22 to receive the valve head 23 normally sealed by the wax plug 24. Depending from the valve head 23 is a standard or solid stem 25 of less diameter than the orifice 26, the standard 25 carrying the spring arms 27 and 28 which are provided 25 with shoulders 29 and 30 to engage the upper face 31 of the cap 32 carried by the barrel 33 which is secured to the head 21 in any appropriate manner. The valve stem 25 is provided with a base 34 at its lower 30 end which may contact with the bottom of the well when the container is lowered therein. When the device constructed in accordance with the form illustrated in Figs. V and VII, both inclusive, is lowered into the 35 well, the base 34 will strike against the bottom thereof and force the valve 23 from its seat to dislodge the wax 24, whereupon the chemicals may be discharged through the orifice 26 and the barrel 33 as clearly indicated in Fig. VI.

After the chemicals have been discharged, the device may be removed from the well to be subsequently recharged in an obvious manner.

45 The plates 18 and 34 serve as deflector plates so that when the chemical is discharged from the receptacle 1 and passes through either the tube 7 or the tube 33, it will strike either the plate 18 or 34, according to the construction used and be deflected 50 toward a horizontal plane so as to be directed into contact with the wall of the well to be attacked by the acid.

As an example of the wax adapted to be 55 used as a sealing medium I will mention paraffin, which may constitute the sealing medium when hydro-chloric acid is employed as a cleaning fluid since hydro-chloric acid will not actively attack paraffin.

From the foregoing it will be apparent 60 that a device constructed in accordance with my invention will enable the operator to locally apply the full charge of chemicals without liability of any of it becoming wasted and thereby enabling the well to be 65 freed of accumulations with a considerably less quantity of chemicals than would ordinarily be employed by known methods.

Having described my invention, what I claim as new therein and desire to secure by 70 Letters-Patent is:—

1. A container for introducing chemicals into an oil well comprising a receptacle with an opening in the bottom thereof, a disruptable seal to close the opening, and a hollow 75 standard having a perforate wall insertible through the disruptable seal, said hollow standard having a discharge opening outside the receptacle.

2. A container for introducing chemicals 80 into an oil well, comprising a receptacle having an opening in the bottom thereof, a disruptable seal to close the opening, a standard slidable through the opening to disrupt the seal, and a transverse baffle carried by the lower end of the standard against 85 which the discharged acid may strike to be deflected in a horizontal plane.

3. A container for introducing chemicals 90 into an oil well, comprising a receptacle having an opening in the bottom thereof, a disruptable seal to close the opening, a standard slidable through the opening to disrupt the seal, a transverse baffle carried by the lower end of the standard against 95 which the discharged acid may strike to be deflected in a horizontal plane, and a latch for holding the standard in its sealed disrupting position.

4. A container for introducing chemicals 100 into an oil well, comprising a receptacle having an opening in the bottom thereof, a disruptable seal normally closing the opening, a normally extended, retractable, sealing member moving longitudinally by pressure to break the disruptable seal to unseal the receptacle, and a transverse baffle carried by the lower end of said unsealing member. 105

5. A container for introducing chemicals 110 into an oil well, comprising a receptacle having an opening in the bottom thereof, a longitudinally movable member for normally closing the opening, a rod connected thereto, and a baffle at the lower end of the 115 rod.

In testimony whereof I affix my signature.
RICHARD E. KIRTLEY.
